UNITED STATES PATENT OFFICE.

GARDINER H. WRIGHT, OF PHILADELPHIA, PENNSYLVANIA, ASSIGNOR TO
F. ODEN HORSTMANN, SAMUEL CLARKSON, WM. P. ELLISON, AND WALTER
HORSTMANN, ALL OF SAME PLACE.

DESIGN FOR A CURTAIN-BAND.

SPECIFICATION forming part of Design No. 13,289, dated September 5, 1882.

Application filed August 7, 1882. Term of patent 7 years.

To all whom it may concern:

Be it known that I, GARDINER H. WRIGHT, a citizen of the United States, and a resident of Philadelphia, Pennsylvania, have invented or produced a new and original Design for a Curtain-Band, of which the following is a specification.

My design for a curtain-band is fully shown in the accompanying drawing. The band is rectangular in outline, and has at each end a loop, *a*. The border of the band is formed by a thick cord, *b*, which is drawn together at each end of the band by tying-cords *d*, the projecting portions of the cord forming the loops *a*. The body of the band is composed of finer cords *f*, which cross each other diagonally, and in each of the diamond-shaped spaces formed by the crossed cords *f* is a ball, *g*, of chenille.

Irrespective of the colors employed, I claim— 20

1. The design for a curtain-band, said design comprising the bordering-cord *b*, the loops *a*, and the tying-cords *d*, as shown and described.

2. The design for a curtain-band, said design comprising the bordering-cord *b*, loops *a*, and crossed cords *f*, as shown and described.

3. The design for a curtain-band, said design comprising the bordering-cord *b*, loops *a*, crossed cords *f*, and balls *g*, as shown and described. 30

In testimony whereof I have signed my name to this specification in the presence of two subscribing witnesses.

GARDINER H. WRIGHT.
